UNITED STATES PATENT OFFICE.

FRANKLIN A. PAPINEAU, OF WEBSTER, MASSACHUSETTS, AND WILLIAM F. PAPINEAU,
OF NEW YORK, N. Y.

SEAM-DETECTOR FOR FABRICS OR THE LIKE.

1,306,713.

Specification of Letters Patent. Patented June 17, 1919.

Application filed December 14, 1918. Serial No. 266,774.

To all whom it may concern:

Be it known that we, FRANKLIN A. PAPINEAU and WILLIAM F. PAPINEAU, residing at Webster, in the county of Worcester and 5 State of Massachusetts, and at New York, in the county of New York and State of New York, respectively, have invented certain Improvements in Seam-Detectors for Fabrics or the like, of which the following 10 is a specification.

This invention relates to detectors, and more particularly to apparatus of this character which is adapted for use in connection with the detection of imperfections in fabrics or the like.

One of the principal objects of the invention consists in the provision of an arrangement whereby varying dimensions, such as 20 seams in fabrics or the like, are detected during their travel through the apparatus. Another object comprises signaling means whereby notice is given to an operator when such imperfections pass through the apparatus. Other and further objects of the 25 invention will hereinafter appear.

In the accompanying drawing, Figure 1 illustrates one embodiment of the invention, the electrical circuit and apparatus forming part thereof being diagrammatically illustrated. Fig. 2 is a sectional view of one of the parts of the device taken on line X, X of Fig. 1.

In the improved detector a base or support 1 is shown. This may be of any suitable construction, and has mounted thereon a plate 2 of some such conducting material as steel, brass or the like. A carrier consisting of oppositely positioned arms 3 and 4 of approximate U-shape form are pivotally and 40 conductively connected at one side to the plate 2. At the opposite side of the arms 3 and 4 are material-engaging members 5 and 6 in the form of rollers, suitably journaled on spindles 7 and 8, and which are adapted 45 to move in the direction in which the fabric travels. The arms 3 and 4 are provided with adjustable tension means 9 by the aid of which the proximity of the rollers 5 and 6 to each other is regulated. Secured to 50 either side and at one end of the base 1 by a strap or other suitable means are upwardly extending post members 10, 10. These members are each provided with resilient contact springs 11 and 12. The springs 55 11 are of greater length than the springs

12, the former being adapted to make contact with the arms 3 and 4 upon their vertical movement, and the latter being adapted to make contact with said members upon their lateral movement. When an imperfection in the fabric, such as a seam or the like passes through the rollers 5 and 6, the members 3 and 4 are capable of lateral or vertical movement, or both, and in either or both movements an electrical circuit will be closed 60 by contact of the members 3 and 4 with the resilient springs 11 and 12. At 13 is shown a contact screw secured to conducting plate 2. Binding posts 14 and 15 are provided at one end of the base 1, said posts being 65 adapted to form terminal connections for the electrical conductors 16, 17 and 18. The conductor 18 is connected to the upper winding of a double wound relay 19. The lower winding of said relay is connected to a release key 20 by way of contact 21 of said key. The contact 21 is strapped to contact 22 adjacent thereto and when the relay is energized a current path is furnished 70 through its lower winding, armature and contact and through the contacts of said key as will later appear. A visual signal 75 or lamp 23 is also provided and will indicate when the relay 19 is energized after the circuit is closed, as will more clearly appear in connection with the description of 80 operation of the device, by the passage of a seam through the machine. It will be understood that the circuit arrangements and 85 apparatus just outlined are individual to one machine. It is customary, however, to provide a number of like machines in a series, each equipped with similar apparatus and circuits. These circuits and apparatus may be connected to conductors 17 and 90 95 31 and to the conductors terminating at 33. A bell 25 which is common to all the machines may be provided to sound an alarm upon the operation of any machine in the series. A master release key 26 is also provided, and functions to break any of the circuits which may be operated in the series. At 34 is shown a cut away portion provided 100 in base 1. This coincides with an aperture in the floor through which the material passes in its travel and may be furnished to give free passage for any overlapping edges of fabric protruding beyond the rollers 5 and 6.

In textile establishments fabric passes 110

from a source of supply, usually in an area below, through the rollers 5 and 6, and the travel of said fabric continues until some such imperfection as a seam is encountered.

5 The members 3 and 4 with their associated equipment are of sufficient weight to remain in horizontal position during the normal travel of the fabric. The passage of the seam through the rollers 5 and 6, however,

10 will cause them to be raised and separated and will thereby convey to the arm members 3 and 4 vertical or lateral movement, or both. In either or both movements the arm members contact with either or both of the

15 spring contacts 11 and 12 and a path for current will be furnished by contact of the arms 3 and 4 with spring contacts 11 and 12 of posts 10, conductors 16 and 17 to binding post 15. By this means contact by either or

20 both of said arm members is insured and a current path is provided over either or both conductors 16 or 17 to binding post 15. From binding post 15 a current path will be established over conductor 17 through contact 27 of master release key 26 to battery and return by way of contact 28 of said key, conductor 31, through upper winding of relay 19, over conductor 18, binding post 14,

25 over conductor, shown in dotted lines, to screw contact 13 secured to plate 2. This circuit provides for the operation of relay 19, which upon energization attracts its armature and a circuit is established over its contact, conductor 29, lamp 23, winding of relay 24, conductor 17, contact 27 of master key 26 to battery and return over contact 28 of said master key, conductor 31, through contacts 21 and 22 of release key 20, back through lower winding of relay 19 to its

30 armature. By this circuit lamp 23 is illuminated, and relay 24 is caused to be energized. The energization of relay 24 provides a circuit whereby bell 25 is operated by a current path from the closed armature of said relay over conductor 32, through said bell to battery, and return by way of conductor 30.

The attendant will be apprised by the sounding of a bell when a seam has passed through any of the machines. The attendant will also be apprised of the particular machine so operated by the illumination of the lamp which is individual to that machine. The lamp may be extinguished by the depression of the release key which controls that particular circuit, and the relay which is also individual thereto will be deenergized, breaking the circuit by which the bell is operated. In the operation of the apparatus here illustrated and which has previously been described, the attendant noting the illumination of lamp 23 and the sounding of bell 25, depresses release key 20, causing it to break its contacts 21 and 22, thereby deenergizing relay 19 and extinguishing lamp 23. Relay 24 will in turn be deener-

gized upon the depression of key 20, and the circuit for bell 25 broken. Should it be more convenient for the attendant, the master release key 26 may be depressed upon the sounding of the bell, or the illumination 70 of any of the lamps in the series, instead of the particular release key associated with an individual machine. In such case the contacts 27 and 28 of key 26 will be broken and the lamp signal of any machine in the series 75 will be extinguished. The circuit for the bell which is common to the series will also in like manner be broken.

The attendant after restoring the circuit conditions to normal will, at a proper time, 80 separate the fabric at a point where the seam occurred. The fabric in the meantime continues in its passage through the material-engaging members until another seam is encountered, whereupon the apparatus 85 will again function as previously outlined.

From the foregoing disclosure it will be seen that by means of this arrangement the attendant will be readily given notice upon the passage of the seam in the fabric as it 90 travels through the apparatus, and by this means loss will be avoided in the production of imperfect fabric.

While there is shown and described herein one preferred form of the invention, by way 95 of illustration, it is understood that it is not limited or confined to the precise details of construction herein described and delineated, as modification and variation may be made within the scope of the claims without 100 departing from the spirit of the invention.

Having thus described our invention, what we desire to secure by Letters Patent is:

1. An apparatus for detecting varying dimensions of traveling material, comprising 105 material-engaging members movable in the direction of travel of the material and toward and from one another under the influence of the variations in dimensions, and indicating means controlled by both movements of the members.

2. An apparatus for detecting varying dimensions of material, comprising a supporting plate, a carrier movable thereon, opposite arms mounted to yield on the carrier and having material-engaging portions, contacts controlled by the yield of the arms and their movement with the carrier, and an indicating circuit governed by the contacts.

3. An apparatus for detecting seams in fabrics, comprising a supporting plate, a carrier movable thereon, opposite arms mounted to yield on the carrier and having material-engaging portions, contacts controlled by the yield of the arms and their movement with the carrier, and an indicating circuit operable upon the passage of seamed fabric through the material-engaging portions.

4. An apparatus for detecting varying dimensions of material, comprising a supporting plate, a carrier movable thereon, opposite arms mounted to yield on the carrier and having material-engaging portions, contacts controlled by the yield of the arms and their movement with the carrier, and a normally open indicating circuit including a visual signal and an audible signal adapted 10 to be closed upon the association of the arms with said contacts.

5. An apparatus for detecting varying dimensions of material, comprising a supporting plate, a carrier movable thereon, opposite arms mounted to yield on the carrier and having material-engaging portions, contacts controlled by the yield of the arms and their movement with the carrier, an indicating circuit adapted to be closed upon the 15 association of the arms with said contacts, a release key, a master release key, and means whereby either key upon depression is adapted to open the closed indicating circuit.

6. An apparatus for detecting seams, a plate member, a carrier comprising members pivotally supported at one of their sides to said plate member, rotatable members journaled to the pivotally supported members at their opposite sides, contacts controlled 20 by the pivotally supported members upon their vertical or lateral movement, and means whereby a circuit is closed by the coöperation of the pivotally supported members and contacts.

35 7. An apparatus for detecting seams, a

plate member, a carrier comprising oppositely positioned arms each pivotally supported at one side to said plate member and having rotatable members journaled at their opposite side, said arms and rotatable members being capable of vertical or lateral movement, adjustable tension means whereby the proximity of the rotatable members to each other is controlled, contact springs adapted to coöperate with said arms upon 40 vertical or lateral movement, and an indicating circuit governed by the association of the contact springs and arms.

8. An apparatus for detecting seams in fabrics, a plate member, a carrier comprising U-shaped arms pivotally supported at one of their sides to said plate member, rotatable members journaled to the pivotally supported members at their opposite sides, contact springs adapted for coöperation with 45 the pivotally supported members upon their vertical or lateral movement, and means whereby a circuit is closed by the passage of seamed fabric through the rotatable members.

In testimony whereof, I have signed my name to this specification this 7th day of December, 1918.

FRANKLIN A. PAPINEAU.

In testimony whereof, I have signed my name to this specification this 4th day of December, 1918.

WILLIAM F. PAPINEAU.
